FOREIGN PATENT DOCUMENTS

TR DM-075166 1/2011

Primary Examiner — Rhea Shields

(74) Attorney, Agent, or Firm — Adibi IP Group, PC;
Amir V. Adibi; Andrew C. Palmer(57) **CLAIM**

The ornamental design for a dozen pastry container, as shown and described.

DESCRIPTION

FIG. 1 is a front perspective view of a dozen pastry container showing my new design.

FIG. 2 is a top view showing my new design.

FIG. 3 is a bottom view thereof.

FIG. 4 is a left side view thereof; the right side view (not shown) being a mirror image thereof.

FIG. 5 is a front view thereof; the back view (not shown) being a mirror image thereof.

FIG. 6 is a front perspective view thereof; showing the dozen pastry container in an environment; and,

FIG. 7 is an exploded view of the dozen pastry container showing my new design.

In FIG. 6, the broken lines are for the purpose of illustrating the environment only and form no part of the claimed design.

1 Claim, 7 Drawing Sheets
